CLAIM

The ornamental design for a lighting fixture, as shown and described.

DESCRIPTION

FIG. 1 is a top perspective view of a new lighting fixture; FIG. 2 is a bottom perspective view thereof; FIG. 3 is a front elevation view thereof; FIG. 4 is a back elevational view thereof; FIG. 5 is a left elevation view thereof; FIG. 6 is a right elevation view thereof; and, FIG. 7 is a bottom plan view thereof. The broken line disclosure represents portions of the fixture which forms no part of the claimed design.
